Primary Examiner—Louis S. Zarfas*Assistant Examiner*—Anhdao Doan(74) *Attorney, Agent, or Firm*—Wenderoth, Lind & Ponack, L.L.P.(57) **CLAIM**

The ornamental design for a line thermal head letter printing apparatus, as shown and described.

DESCRIPTION

FIG. 1 is a front view of a line thermal head letter printing apparatus of the present invention;

FIG. 2 is a rear view of the design;

FIG. 3 is a left side view of the design;

FIG. 4 is a perspective view of the design;

FIG. 5 is a top view of the design;

FIG. 6 is a bottom view of the design; and,

FIG. 7 is a right side view of the design.
